Primary Examiner — John R Yeh*(74) Attorney, Agent, or Firm* — Guy V. Manning**CLAIM**

The ornamental design for a child's play desk as shown and described.

DESCRIPTION

FIG. 1 is a front, left, elevated, quartering perspective view of a new design for a child's play desk;

FIG. 2 is a top plan view of the new design of FIG. 1;

FIG. 3 is a bottom plan view of the new design of FIG. 1; FIG. 4 is a front elevational view of the new design of FIG. 1, the rear elevational view thereof being a mirror image of FIG. 4;

FIG. 5 is a right-side elevational view of the new design of FIG. 1, the left side elevational view thereof being a mirror image of FIG. 5; and,

FIG. 6 is a front, left, lowered, quartering perspective view of the new design of FIG. 1.

Dashed lines included within the figures (FIGS. 3, 6) surround areas that do not form part of the claimed design.
